UNITED STATES PATENT OFFICE.

EDMUND I. CUTTER, OF CINCINNATI, OHIO, ASSIGNOR TO THE AMERICAN LAUNDRY MACHINERY COMPANY, OF NORWOOD, OHIO, A CORPORATION OF OHIO.

DRYING TUMBLER.

1,424,994.

Specification of Letters Patent. Patented Aug. 8, 1922.

Application filed April 23, 1920. Serial No. 376,136.

To all whom it may concern:

Be it known that I, EDMUND I. CUTTER, a citizen of the United States, residing at Cincinnati, in the county of Hamilton and State 5 of Ohio, have invented certain new and useful Improvements in Drying Tumblers, of which the following is a specification.

This invention relates to the class of laundry machines and more especially to the type 10 known as drying tumblers, the improvement in this case being directed to an arrangement of the several chambers in the machine casing whereby the heating chamber can be either included in or excluded from the circuit of 15 the air through the machine by a single operation of the mechanism which controls the passage-ways between the several chambers.

This type of machine generally includes 20 an air chamber, a heating chamber, and a drying chamber with communicating passage-ways between the several chambers. The air and blower chamber communicate with the outside atmosphere whereby fresh air may be drawn into the machine casing 25 by the action of the fan, and the warm air expelled through an outlet in the machine casing after it has been passed through the drying chamber. During the operation of drying the materials in the tumbler the fresh 30 air from the outside atmosphere is forced through the heating chamber and thence through the drying chamber, and back to the blower from which point it is expelled in part or in whole to the outside. But when 35 the drying operation has been completed it is desirable to cool the materials in the drying tumbler preparatory to their removal therefrom, and this is done by circulating the fresh outside air through the drying chamber 40 without being heated. This is done by cutting out the heating chamber from the circuit of the air through the machine, and the applicant has devised a convenient arrangement of doors or dampers which control the 45 passage-ways between the several chambers, together with a single operating mechanism for controlling the positions of these several dampers. By means of applicant's device he is enabled to establish either one or the other 50 of the two circuits of air just referred to by a single operation. That is to say, he can so set the dampers by a single operation that the air will be forced from the outside atmosphere through the heating chamber, thence 55 through the drying chamber and back to the

blower chamber. Or, by a single operation he can establish direct communication between the outside atmosphere and the drying chamber, and in turn the blower chamber in which case the heating chamber is altogether 60 excluded from the circuit of air through the machine.

Other advantages resulting from applicant's invention will be apparent to those who are familiar with the art, and other 65 structural arrangements will suggest themselves for carrying out the invention as herein disclosed.

The structural arrangement embodying 70 applicant's invention as prepared by him will be understood from the following description and claims when considered in connection with the accompanying drawing:

Fig. 1 is an elevation of the machine casing showing a single operating means for 75 adjusting the positions of the dampers; Fig. 2 is a transverse section through the machine showing arrangement of the several chambers and the dampers for controlling communication therebetween; Fig. 3 is a sec 80 tional detail view taken on line *a*—*a*, Fig. 2; Fig. 4 is a sectional detail view taken on line *b*—*b*, Fig. 2; Fig. 5 is a sectional detail view taken on line *c*—*c*, Fig. 2; Fig. 6 is a horizontal sectional view taken on the plane 85 of line *d*—*d*, Fig. 2; and Fig. 7 is a sectional view of part of the operating mechanism taken on line *e*—*e*, Fig. 1.

The lower part of the machine casing 1 constitutes a heating chamber 3, while the 90 upper part of the casing is divided into a blower chamber 2 and the drying chamber 4. The partition wall 43, which extends between the heating chamber and the upper part of the machine casing, has a passage- 95 way 17' provided therein for communication between the heating chamber and the drying chamber. Above one part of partition 43 there extends a second partition member 24 which serves to separate a fresh air chamber 100 5 from the main part of air and blower chamber 2. 5^ indicates the fresh air opening for fresh air chamber 5. This partition wall 24 is an extension of the partition wall 23 which extends between the drying chamber 105 2 and main part of air and blower chamber 2. A passage-way is provided between the fresh air chamber 5 and the drying chamber 4, this passage-way being controlled by the damper 16 which is hingedly mounted 110

upon the shaft 19, and the damper 15 hingedly mounted upon its shaft 20 controls the passage-way between the fresh air chamber 5 and the heating chamber. The passage-way 17' may be closed or opened by operation of the damper 17 upon its axis 18 which is mounted upon the I-beam 30. Damper 17, when occupying closed position, contacts with shoulder 18' which is formed upon the end portion of partition 43. A stop 16' is also provided upon partition wall 43 to limit the movement of damper 16 upon being brought to closed position.

The air and blower chamber 2 encloses a housing 6 for a fan 7, whose operating shaft is indicated at 8, this fan being adapted to expel the warm air through outlet 22 which is provided in the casing wall of the machine.

20 The heating chamber encloses the steam coils 9 between which there are provided baffle plates 10 and spacing rods 11, all of which are mounted upon a truck which is adapted to be removed from the heating chamber as a unit through a door at either end of the machine casing. This arrangement will be more fully understood from the detail description found in companion application filed of even date and bearing Serial 30 No. 376,135.

The drying chamber encloses a cylindrical tumbler having a foraminous wall 12 allowing the passage of air therethrough, and a door 13 which allows access to the materials contained therein upon opening door 14 which is provided in the machine casing. Baffle members 21 are also provided within the drying chamber. The drying tumbler, which is mounted upon shaft 23^a, receives its operation through gear 24 carried by shaft 23^a, which gear meshes with gear 25 upon shaft 26, gear 25 meshing with gear 27 upon the shaft 28, which shaft receives its operation from pulley wheel 29. Shaft 28 is supported by bracket member 31 mounted upon the machine casing. The source of power is not here shown, neither is the particular mechanism shown whereby the usual back and forth rotation of the drying cylinder is effected, this being old and well known in the art.

Coming now to the particular mechanism for operating the several dampers, it will be seen from Fig. 1 that upon manipulation of wheel 39 adjustment of the three dampers upon their axes 18, 19 and 20 may be effected by a single operation. Lever arm 45 which is fixedly mounted upon shaft 20 carries clevis 45' which is connected to the flattened face of member 46 which is screwed on rod 47. Another similar member 48 on the other end of rod 47 has pivotal connection with the clevis end 49' on the longer arm of bell crank lever 49, which is mounted 65 at its fulcrum upon shaft 19 of damper 16.

A clevis 50 provided upon the shorter arm of bell crank lever 49 has pivotal engagement with the flattened end of member 51 on connecting rod 52, the other end of rod 52 carrying a member 40 with a flattened end portion which has pivotal engagement with clevis 41' on lever arm 41 mounted upon shaft 18 of damper 17. Substantially midway of the length of connecting rod 52 there is mounted a swivel block 53 which has 70 swivel connection with one end of a lever arm 32 which is mounted at 33 in the side wall of the machine casing. Lever arm 32 is pivotally connected at 34 with one end of an operating rod, part of which is screw 80 threaded as shown at 37. Screw thread engagement is had between this operating rod and the swivel nut 36 pivotally mounted at 42 in the side wall of the machine casing, a set screw 44 being provided for securing this nut in the position to which it is adjusted.

Stops 35 and 38 are provided upon the operating rod, the distance between these two stops corresponding to the extent of adjustment which is necessary in order to 90 change the several dampers from one position to another. That is to say, when the operating rod has been manipulated by means of wheel 39 until stop 35 is brought to bear against nut 36, the damper 16 will 95 be opened while dampers 15 and 17 will be closed, thereby excluding the heating chamber from the circuit of air through the machine. When stop 38 is brought to bear against nut 36 the reverse condition is established. That is to say, the heating chamber is included in the circuit of air through the machine by virtue of the fact that damper 16 is closed and the other two 100 dampers 15 and 17 are open. Thus by simply operating manipulating hand wheel 39 so as to bring the operating rod into either one or the other of these two positions, the circuit of air through the machine can be 105 changed as desired, depending upon whether the materials in the tumbler are in the process of being dried, or whether it is desired to cool the materials after the drying process preparatory to their removal from 110 the machine.

What I claim is:

1. In a drying machine, the combination of an air and blower chamber, a heating chamber, a drying chamber, said several chambers having communicating passage-ways therebetween, means for forcing air through said chambers, dampers for controlling the passage-ways between said several chambers, and a single operating means for adjusting the positions of said several 120 dampers whereby communication can be established between all or only some of said chambers.

2. In a drying machine, the combination of a blower and air chamber, a heating 130

- chamber, a drying chamber, said several chambers having communicating passage-ways therebetween, means for forcing air through said machine, dampers for passage-ways between said several chambers, and a single operating means for controlling the positions of said dampers whereby the heating chamber can be either included in or shut off from the circuit of air through the machine.
3. In a drying machine, the combination of a blower and air chamber, a heating chamber, a drying chamber, said several chambers having communicating passage-ways therebetween, means for forcing air through said machine, dampers for passage-ways between the air and drying chambers, the air and heating chambers, the heating and drying chambers respectively, and a single operating means for closing the first named damper and opening the other two dampers, or vice versa, whereby the heating chamber can be included in or excluded from the air circuit through the machine.
4. In a drying machine, the combination of a blower and air chamber, a heating chamber, a drying chamber, said several chambers having communicating passages therebetween, means for forcing air through said machine, hingedly mounted dampers for the passage-ways between said several chambers, and a single operating means for adjusting the positions of said dampers, whereby communication can be established between all or only some of said several chambers.
5. In a drying machine, the combination of a blower and air chamber, a heating chamber, a drying chamber, said several chambers having communication therebetween, means for forcing air through said machine, hingedly mounted dampers for the passage-ways between said several chambers and operative connections between the hinge shafts of the said several dampers whereby the adjustment of one of said dampers will effect corresponding adjustment of the other of said dampers.
6. In a drying machine, the combination of a blower and air chamber, a heating chamber, a drying chamber, said several chambers having communicating passage-ways therebetween, means for forcing air through said machine, hingedly mounted dampers for the passage-ways between the air and drying chambers, the air and heating chambers, the heating and drying chambers respectively, and operative connection between the hinge shafts of said dampers whereby the closing of first named damper will effect the opening of the other two dampers, and vice versa.
7. In a drying machine, the combination of a blower and air chamber, a heating chamber, a drying chamber, said several chambers having communication therebetween, means for forcing air through said machine, hingedly mounted dampers for the passage-ways between the air and drying chambers, the air and heating chambers respectively, operative connections between the hinge shafts of said dampers, and an operating member having an operative connection with the said first named operative connections whereby the closing of the first named damper will effect opening of the other two dampers, and vice versa.
8. In a drying machine, the combination of a blower and air chamber, a heating chamber, a drying chamber, said several chambers having communicating passage-ways therebetween, means for forcing air through said machine, hingedly mounted dampers for the passage-ways between the air and drying chambers, the air and heating chambers, the heating and drying chambers respectively, operative mechanical connections between the hinge shafts of said dampers and an operating member having connection with the first named operative connections at a point between the first and last named dampers.
9. In a drying machine, the combination of a blower and air chamber, a heating chamber, a drying chamber, said several chambers having communicating passage-ways therebetween, means for forcing air through said machine, dampers for the passages between the air and drying chambers, the air and heating chambers, the drying and heating chambers respectively, and means for simultaneously closing the first named damper and opening the other two dampers, or vice versa, whereby the heating chamber can be either included in or excluded from the circuit of air through the machine.
10. In a drying machine, a control mechanism comprising a bell crank lever with arms of different lengths, a rod pivotally connected at one end to the longer arm of the bell crank lever, a lever arm adapted to be mounted on the shaft of a damper and pivotally connected to the other end of said rod, said bell crank lever being adapted to be mounted at its fulcrum upon the hinge shaft of another damper, a lever arm adapted to be mounted upon the hinge shaft of a third damper, a connecting rod having its ends pivotally connected to the free end of said last named lever arm and to the end of the shorter arm of said bell crank lever respectively, said connecting rod having a swivel block mounted substantially midway of its length, a straight lever arm adapted to be mounted at its middle point upon the casing of a drying machine, one end of said last named lever arm having swivel connection with said swivel block, a screw thread-

ed operating rod provided with stops at the ends of the screw thread, and having pivotal connection with the other end of said last named lever, a swivel nut having screw 5 thread engagement with said operating rod and a pivot member formed upon said swivel nut for attachment to the casing of a drying machine, the distance between the stops on said operating rod corresponding to the 10 range of movement of the several dampers in a drying machine from open to closed positions, or vice versa.

11. In a drying machine, the combination of a blower and air chamber, a heating 15 chamber, a drying chamber, said several chambers having communicating passage-ways therebetween, means for forcing air through said machine, said drying machine having a door opening to the drying chamber, doors for the passage-ways between said several chambers, and a single operating means for controlling the positions of said doors whereby the heating chamber can be either included in or excluded from the circuit of air through the chamber, said operating means being operable from a point 20 near the said casing door.

12. In a drying machine, a casing, the lower part of said casing constituting a heating chamber, the upper part of said casing 25 being divided into a drying chamber and an air and blower chamber, the lower part of said last named chamber being further partitioned into a fresh air chamber, said fresh 30 air chamber having a communicating pas-

sage-way at one end with said heating chamber and at its other end a communicating passage-way with said drying chamber, said heating and drying chambers also having a communicating passage-way, and said drying 40 chamber having communication with said air and blower chamber, and dampers pivoted upon horizontal axes for control of the said several passage-ways.

13. In a drying machine, a casing, the lower part of said casing constituting a heating chamber, the upper part of said casing being divided into a drying chamber and an air and blower chamber, said casing being 45 also provided with a fresh air inlet adapted for communication with said heating chamber or said drying chamber, said heating and drying chambers being also provided with means of communication, and said drying chamber having communication with said air and blower chamber, and dampers for 50 control of the said several communicating means.

14. A drying machine comprising a casing enclosing a heating chamber in the lower 55 part thereof and drying and fan and air chambers above said heating chamber, said casing being provided with inlet and outlet openings and means of communication between said openings and chambers for circulation of air therethrough, and dampers for simultaneous control of said communicating means.

In testimony whereof I affix my signature.
EDMUND I. CUTTER.
